UNITED STATES PATENT OFFICE.

WALTER G. DOTY, OF DAYTON, OHIO.

DESIGN FOR A SUCTION-CLEANER NOZZLE.

47,063.

Specification for Design.

Patented Mar. 2, 1915.

Application filed June 4, 1914. Serial No. 843,108. Term of patent 3½ years.

To all whom it may concern:

Be it known that I, WALTER G. DOTY, a citizen of the United States, residing at Dayton, in the county of Montgomery and State of Ohio, have invented a new, original, and ornamental Design for Suction-Cleaner Nozzles, of which the following is a specification, reference being had to the accompanying drawing, forming part thereof.

Figures 1 and 2 are a plan view and a side elevation, respectively, of a suction cleaner nozzle showing my new design.

I claim:

The ornamental design for a suction cleaner nozzle, as shown.

WALTER G. DOTY.

Witnesses:

C. A. CRAIGHEAD,
CARRIE M. RECKER.
